ARTICLE CONTROLLED ADJUSTMENT FOR
PACKAGING APPARATUS

James Arthur Kay, Gainsborough, England, assignor to Rose Brothers (Gainsborough) Limited, Gainsborough, England, a British company

Application October 5, 1944, Serial No. 557,330
In Great Britain June 9, 1943

Section 1, Public Law 690, August 8, 1946
Patent expires June 9, 1963

15 Claims. (CL 93—6)

1

This invention relates to packaging apparatus of the kind that is adjustable for the accommodation of articles, e. g. fibreboard containers, of different width and/or height and wherein the adjustment of the apparatus is controlled by a controlling device, which automatically causes appropriate adjustment of the apparatus upon movement of a controlling member to a position appropriate to the size of the article for which the apparatus is to be adjusted.

According to the invention there is provided an apparatus of the kind described, wherein the movement of the controlling member is brought about by a movable feeler member connected to the controlling member and arranged to engage each article in turn as it is fed to the apparatus so as to cause the controlling member to move to a position appropriate to the size of the article for the time being in engagement with the feeler member thereby causing the controlling device to bring about adjustment of the apparatus appropriate to that article. The feeler member may be arranged in the path followed by the articles as they are fed to the apparatus so as to be moved outwardly by each article in turn, means being provided for continually urging the feeler member into engagement with the articles.

Where the apparatus is adjustable as regards both width and height of the articles, two movable feeler members may be employed for operating respectively the controlling members associated with the adjustment of the apparatus as regards the width and height of the articles.

By the use of the present invention, therefore, articles of different dimensions may be fed in succession to the apparatus, each article automatically bringing about any adjustment of the apparatus to suit its own dimensions.

When each article is of a different size to the succeeding one, it will, of course, be necessary for each article to pass completely through the adjustable portion of the apparatus before adjustment takes place for the next succeeding article, and to allow of this, stop members, operating in conjunction with the feeler mechanism and controlling device, are provided for preventing entry of one size of article into the adjustable portion of the apparatus while an article of a different size is passing through. Means may be provided, however, for rendering the controlling device ineffective while any article is passing through the adjustable portion of the apparatus so as to allow the next succeeding article to operate the feeler mechanism to set the controlling device in advance for the next adjusting opera-

2

tion, adjustment then taking place immediately the adjustable portion of the apparatus is free from articles. In such a case, means may be provided in association with the feeler mechanism for rendering the controlling device and the stop members ineffective when successive articles are of the same size so that such articles may pass through the adjustable portion of the apparatus at the same time.

10 By way of example, the invention will now be described in greater detail with reference to the accompanying diagrammatic drawings, in which,

Figure 1 is an elevation of the front end of a packaging apparatus constructed in accordance with the invention,

Figure 2 is a plan view of the apparatus shown in Figure 1.

Figure 3 is an end view of part of the apparatus shown in Figure 1 viewed in the direction of the arrow shown in Figure 1.

Figure 4 is a wiring diagram showing the various electrical connections,

Figure 5 is an elevation of an intermediate portion of the packaging apparatus, and is a continuation from the left-hand side of Figure 1,

Figure 6 is a plan view of the portion of the apparatus shown in Figure 5,

Figure 7 is an elevation of a portion of the apparatus shown in Figure 1, drawn to a larger scale than Figure 1,

Figure 8 is a plan view of the apparatus shown in Figure 7, and

Figure 9 is an enlarged view of a detail of Figures 7 and 8.

35 The packaging apparatus shown in the drawings is for closing and sealing the flaps of travelling open-ended containers which have previously been filled, the containers 11 being fed through the apparatus by means of pusher bars 184 carried by a pair of chains 184, and delivered with their flaps freshly sealed to a conveyor (not shown) for transferring the sealed containers to another station.

40 The packaging apparatus is adjustable both as regards the width of the container and its height so as to be capable of accommodating containers of various sizes. The general construction and operation of the adjustable portion of the apparatus is known so that it is only necessary to describe in detail such parts of the adjustable mechanism as are necessary for a full understanding of the construction and operation of the apparatus according to the invention.

45 The parts of the apparatus that need to be adjusted when it is desired to adjust the apparatus

in regard to the height of the container (hereinafter referred to as the "vertically adjustable parts") are supported on a pair of brackets 220 slidably mounted on pairs of pillars 216 and 217 and their adjustment is controlled by pairs of vertical screwed shafts 219, only one pair of which is shown. The parts of the apparatus that it is necessary to adjust when it is desired to adjust the apparatus as regards the width of the container (hereinafter referred to as the "laterally adjustable parts") are slidably mounted on supporting shafts 227 and 228, running transversely of the path of the containers 11, and the adjustment of these parts is brought about by horizontal screwed shafts 231 and 233. The laterally adjustable parts include side guides 236 and 113.

The vertical screwed shafts 219 are driven through suitable gearing from a reversible electric motor 236 while the horizontal screwed shafts 231 and 233 are similarly driven from a further reversible electric motor 239. The motors 233 and 239 are provided with solenoid brakes 241 and 242, respectively, of the well-known type in which the brake is normally maintained in operation by means of a spring and is released against the spring pressure when the solenoid is energized.

The operation of the apparatus according to the invention will first be described in general terms and the construction and operation of the various mechanisms will then be described more fully. Referring to Figures 1 to 3, containers 11 are fed to the apparatus in succession but during the feeding movement, i. e., before the containers reach the adjustable portion of the apparatus, they pass through a measuring station 12 where they are temporarily halted in turn. As the leading container moves into the measuring station, it engages a pair of feeler members 13 and 14 lying in its path, the feeler 13 (the height feeler) being arranged to engage the top and the feeler 14 (the width feeler) one side of the container. The containers are fed by a conveyor 16 provided with guide rails 17 spaced apart sufficiently to accommodate the widest container in the range for which the apparatus is built, the conveyor 16 being inclined towards the side of the conveyor opposite to that on which the width feeler 14 is arranged so as to urge the containers continuously towards that side of the conveyor, and also inclined downwardly in a forward direction so as to feed the containers forward, a fixed stop 18 being provided on that side of the conveyor for the purpose of arresting the bulk of the containers while the leading one moves into the measuring station. First and second movable stop members 19 and 21 are also provided for controlling the movement of the containers into and out of the measuring station 12.

As the leading container reaches the measuring station 12, it is temporarily arrested by the second stop member 21 until the measuring operation is completed.

By the time the leading container reaches the second stop member 21, the feeler members 13 and 14 have been moved upwardly and outwardly, respectively, by the container by amounts corresponding to its height and width, respectively. Such movements of the feeler members 13 and 14 are transferred to the controlling members 22 and 23, respectively, of a controlling device generally indicated by reference numeral 246.

The controlling device 246 consists of two

units 247 and 248, 247 for controlling the movement of the laterally adjustable parts (hereinafter referred to as the lateral unit) and 248 for controlling the movement of the vertically adjustable parts (hereinafter referred to as the vertical unit). The lateral and vertical units are driven from the motors 239 and 238, respectively, through the medium of the screwed shaft 233 and one of the screwed shafts 219, respectively. The driving connections are as follows:

In the case of the lateral unit 247, the motor 239 drives a vertical shaft 249 through a pair of spiral gears 251, and the vertical shaft 249 drives the screwed shaft 233 through a worm reduction gear 252. Secured to the screwed shaft 233 is a spiral gear 266 arranged in mesh with a further spiral gear 267 secured to the driving shaft 269 for the lateral unit, the driving shaft 269 having one bearing in an extension 271 of the main framework and another in the framework of the controlling device 246.

In the case of the vertical unit 248, one of the screwed shafts 219 (the one disposed on the same side of the apparatus as the controlling device 246) has secured to its lower end a spiral gear 276 arranged in mesh with a further spiral gear 277 secured to the driving shaft 282 for the vertical unit 248, the driving shaft 282 having one bearing in an extension 283 from the main framework and another in the framework of the controlling device 246.

The construction and operation of the controlling device 246 will now be described with particular reference to Figures 7, 8 and 9.

The device is mounted in a framework 291 of box section in which are arranged the lateral and vertical units 247 and 248 respectively. The lateral and vertical units are identical in construction and co-operate respectively with the motors 239 and 238 and their solenoid brakes 242 and 241 in a manner which will be apparent from the following description in which only the lateral unit 247 is described. The drive shaft 269 drives a vertical shaft 301 through a worm reduction gear 302, the vertical shaft 301 being provided with bearings in bearing members 303 and 304, forming part of the framework 291. Secured to the upper end of the vertical shaft 301 is a rotatable member comprising a pair of arms 306 and 307 extending from a hub portion 308 and terminating in bearings 309 and 311. Pivoted in the bearings 309 and 311 is a pair of starting members generally indicated by reference numerals 312 and 313. The starting member 312 consists of a pair of rods 314 attached at one end to a shaft 316 supported in the bearing 309 and carrying at their other ends an arcuate track 317. The starting member 313 is identical with the starting member 312 and consists of a pair of rods 318 attached at one end to a shaft 319 supported in the bearing 311 and carrying at their other ends an arcuate track 321. The tracks 317 and 321 are disposed symmetrically about the axis of the vertical shaft 301 and are separated by a gap 322 (see Figure 9).

The starting members 312 and 313 carry pairs of spring-loaded plungers 323, 320 and 324, 325, respectively, which are arranged to co-operate, respectively, with pairs of micro-switches 47, 88 (44, 86 vertical units) and 48, 89 (46, 87 vertical units), attached to the hub portion 308 of the rotatable member at positions immediately below the pairs of plungers 323, 320 and 324, 325, and connected in the circuit of the motor 239 and

the solenoid brake 242 in such a manner that the switches operate to start the motor 239, energize the solenoid of the brake 242, and operate the stop members 19 and 21 in the manner described below. The switches 88 and 89 (the motor switches) are connected in the motor circuit in such a manner that one switch causes the motor to rotate in one direction and the other causes the motor to rotate in the opposite direction.

Formed in the upper cover plate of the framework 291 is a bearing 345 in which is arranged a vertical shaft 343 arranged for pivotal movement about an axis coincident with that of the vertical shaft 301. Secured to the upper end of the shaft 343 is an arm 17 (the purpose of which will be described later), and at the lower end of the shaft (inside the framework 291) is secured the controlling member 23. Freely mounted in suitable bearings formed at the extremity of the controlling member 23 is a roller 356 arranged to engage the tracks 317 and 321 which are urged into contact with the roller 356 by springs 351 carried by pins 358 the upper portions of which are provided with shoulders 359 which act as stops to limit the upward movement of the track. When the unit is inoperative, the roller 356 bridges the gap 322, as shown in Figure 9, in which position the micro-switches 88 and 89 are in the "off" position.

Pivotal movement of the controlling member 23 in response to movement of the feeler member 14, in one direction or the other, causes the roller 356 to depress the arcuate track 317 or 321, as the case may be, so that the corresponding starting member 312 and 313 is caused to pivot about the axis of the shaft 316 or 319 during which movement the corresponding pair of plungers 323, 320 or 324, 325 operate the corresponding pair of micro-switches 47, 88 or 48, 89, as the case may be, operation of which causes the solenoid of the solenoid brake 242 to be energized to release the brake and at the same time causes the motor 239 to be set in motion in the appropriate direction. The screwed members 231, 232 and 233 are then caused to rotate through their geared connection with the motor 239 to bring about adjustment of the laterally adjustable parts of the adjustable mechanism, and the screwed shaft 233 causes the vertical shaft 301 to rotate through the geared connection described above, with the result that the rotatable member is set in motion in the same direction as that in which the controlling member 23 has been rotated and continues its motion until the gap 322 reaches the roller of the controlling member 23 in the position to which it has been moved under the influence of the feeler member 14, whereupon the arcuate track 321 is caused to snap back under the influence of the spring 351 into its original position (see Figure 9), this movement withdrawing the plungers 324 and 325 to disconnect the micro-switches 47 and 88 thereby stopping the motor 239 and de-energizing the solenoid of the brake 242 so that the brake is automatically applied. It will thus be seen that the roller 356 will maintain the arcuate track 321 in its switch-operating position until such time as the rotatable member has made an angular movement corresponding to the displacement of the roller 356 with respect to the gap 322. It will thus be seen that the controlling members 22 and 23 are moved in response to the movement of the feeler members to positions corresponding to the dimensions of the container.

for the time being at the measuring station and bring about adjustment of the adjustable portion of the apparatus to suit that container. As soon as the adjustment is complete, the stop members 19 and 21 are moved out of the path of the container so as to allow the leading container to move out of the measuring station and the next succeeding one to move in whereupon the process is repeated. Operation of the stop members 19 and 21 is brought about by solenoids 24 and 26, respectively, which are so controlled that when the controlling device comes to rest after an adjusting operation the solenoids are energized and cause the stop members to move to their inoperative positions.

It will be understood that when each container fed to the apparatus is of a different size from the preceding one, it will be necessary for each container to pass completely through the adjustable portion of the apparatus before adjustment can be effected to suit the next succeeding container, and to allow of this, there is provided in the adjustable portion of the apparatus a feeler bar 27 arranged to be depressed by any container passing through the adjustable mechanism to operate a safety switch 28 for rendering the controlling device inoperative. The feeler bar 27 is pivotally mounted on links 372 attached to the lower side guides 236 and 113 and urged towards the containers 11 by springs 373. The feeler bar 27 carries a plunger 374 arranged to operate the switch 28 when the feeler bar is depressed outwardly by any container passing through the adjustable mechanism. The switch 28 is of the type which is normally closed, i. e., the circuit in which the switch is connected is complete when the plunger 374 is out of contact with the switch, and is connected in the circuit governing the operation of the controlling device 246. It will thus be seen that, when there are no containers passing through the adjustable mechanism, the circuit is complete and the controlling device can be operated, and that when containers are passing through the adjustable mechanism the feeler bar is depressed with the result that the switch 28 is operated to break the circuit so that the controlling device becomes inoperative (except in certain circumstances described below). The safety switch 28, when open, serve also to de-energise the solenoids 24 and 26 operating the first and second stop members 19 and 21 so that those members can spring up into stop position thus preventing the next succeeding container from entering the adjustable portion of the apparatus.

When, however, two or more successive containers are of the same dimensions, it is desirable that they should be allowed to pass through the apparatus at the same time, and for this reason, there is arranged in association with each feeler member 13 and 14 equalizer switches 29 and 31, respectively, arranged to co-operate with an adjustable part of the apparatus in such a manner that when a given container is of the same dimensions as the preceding one the equalizer switches 29 and 31 are operated to close the circuit that has been opened by the safety switch 28, thereby energizing the solenoids 24 and 26 so as to cause the stop members 19 and 21 to move into their inoperative positions and thus allow the next container to move into the adjustable portion of the apparatus.

As the containers 11 are fed by the conveyor 16 they first meet the fixed stop 18 as explained above, and each one is pushed clear of the stop

18 by a pusher bar 41 the movement of which is controlled by the solenoid 24 through parallel motion linkages 42 and 43, in timed relation to the movement of the stop member 19. The construction is such that as the stop member 19 is moved downwardly to its inoperative position by the solenoid 24, the pusher bar 41 moves forward to move the leading container clear of the fixed stop 18. The solenoid 24, in common with the solenoid 26 operating the stop member 21, is operable by the microswitches 44, 46, 47 and 48 under the control of the controlling members 22 and 23. The microswitches 44, 46, 47 and 48 are of the normally closed type so that the solenoids 24 and 26 are operative to maintain their respective stop members in their inoperative positions when the controlling members 22 and 23 are in their neutral positions, or when the controlling device is ineffective. Assuming the leading container to be just passing into the measuring station 12, it will be seen that, as soon as the container moves the feelers 13 and 14 (which are designed in this instance to return by gravity to the positions corresponding to the minimum sized container) the controlling members 22 and 23 immediately operate the microswitches 44 and 47 or 46 and 48, according to the direction of rotation, whereupon the solenoids 24 and 26 become ineffective and the stop members 19 and 21 spring into stop position through the action of the springs 49 and 51, respectively, the stop member 21 arresting movement of the leading container at the measuring station and the stop member 19 arresting the movement of the bulk of the containers on the conveyor 16 in co-operation with the fixed stop 18.

The feeler member 13 is carried by a shaft 52 pivotally mounted in a pair of arms 53 supported on a shaft 54 itself pivotally mounted in a pair of frames 56 extending from the main framework of the apparatus. Also secured to the shaft 52 is an arm 57 carrying a roller 58 arranged to bear in a vertical slot 59 in one of the frames 56. Carried on the stud 61 carrying the roller 58 is a rack 62 arranged to engage a pinion 63 mounted on a shaft 64 carried in bearings 66 and 67 provided on the frame 56 and the controlling device respectively. A guiding roller 68 is mounted on the main framework of the apparatus and is arranged to maintain the rack 62 in engagement with the pinion 63. Also attached to the shaft 64 is a spiral gear 69 arranged to engage a further spiral gear 71 secured to the shaft 72 carrying the controlling member 22. The tip of the feeler member 13 is in line with the centre of the roller 58, and the operative edge of the stop member 21, which is pivoted on a shaft 73 extending between the main frames of the apparatus, is also in vertical alignment with the centre of the roller 58 when the feeler member is in its stop position.

The feeler member 14 is pivotally mounted on a shaft 74 carried by a bracket 75 extending from the main framework of the apparatus and is formed with an arm 76 extending downwardly and being connected to the arm 77 by means of a link 78. It will be seen, therefore, that as the container at the measuring station moves the feeler members 13 and 14, they in turn move the controlling members 22 and 23 to positions on the controlling device appropriate to the size of the container, whereupon the controlling device causes the apparatus to be adjusted to suit that particular container.

The motors 238 and 239 controlling the adjustment of the apparatus are controlled by the

microswitches 86, 87, 88 and 89 as described above. The pairs of switches are 44 86, 46 87, 47 88, and 48 89 (see particularly Figure 4), and the switches constituting each pair are operated synchronously upon movement of the controlling members 22 or 23. The motor switches 86, 87, 88 and 89 are of the normally open type, whereas, as explained above, the solenoid switches 44, 46, 47 and 48 are of the normally closed type, so that, when the motors are operated, the solenoids are de-energized and vice versa.

From the measuring station, the container is fed forward by a belt 79 the upper lap of which is supported at intervals on rollers 81. The belt 79 is driven by means of chain and sprocket gearing 82 from the shaft 83 carrying the main feed chain 84 of the apparatus.

Assuming a container to be still at the measuring station, and the operation of the adjusting mechanism just completed, it will be seen that the motor switches 86 or 87 and 88 or 89, as the case may be, have just been closed while the solenoid switches 44 or 46 and 47 or 48 have just been opened. This operation would normally energise the solenoids and cause the stop members 19 and 21 to be withdrawn to their inoperative positions so as to allow the container at the measuring station to move forward and the next succeeding container to take its place.

As mentioned above, however, there is provided in the adjustable portion of the apparatus a safety switch 28 which renders the controlling device inoperative (except in the circumstances mentioned below) during the time that a container or containers are passing through the adjustable portion of the apparatus. This being the case, the solenoids 24 and 26 are prevented from operating until such time as the adjustable portion of the apparatus is free from containers when the safety switch 28 is once more closed and the solenoids 24 and 26 operate to allow the container at the measuring station to move forward and the succeeding one to take its place.

The safety switch 28 is operated, as described above, by a feeler bar 27, which in this example, extends through the adjustable portion of the apparatus to a point just short of the vertical line containing the axis of the roller 58, so that, as soon as the container for the time being at the measuring station is released for forward movement, the safety switch 28 is operated by the feeler bar 27, thus rendering the controlling device inoperative.

From the measuring station the container is moved forward by the belt 79 until it meets the second fixed stop 91 from which it is freed in timed relation to the movement of the pusher bars on the main chain 84 by means of a further pusher 92 which is reciprocated by a two-armed lever 93 in co-operation with a rotatable cam 94 in known manner. The container then moves into the main portion of the apparatus in the ordinary way.

As mentioned above, there is arranged in association with each feeler member 13 and 14 equalizer switches 29 and 31, respectively, the purpose of these being to allow containers of the same dimensions to proceed into the adjustable portion of the apparatus at the same time. The equalizer switch 29 is mounted on the rack 62 and is arranged to co-operate with a contact member 101 carried by a vertical rack 102 mounted in bearings 103 extending from the framework 56, the rack being driven by a pinion 104 mounted on a shaft 105 having one bearing

107 in the framework 56 and another bearing 105 forming part of the main framework of the adjustable portion of the apparatus. The shaft 106 is driven by a rack and pinion mechanism 110 and 210, similar to that just described, the racks 110 being secured to the adjacent bracket 220 for movement with the vertically adjustable parts. It will thus be seen that as the rack 62 is raised by the feeler 13 as a container moves into the measuring station, the consequential movement of the adjustable portion of the apparatus causes the contact member 101 to be adjusted up or down, as the case may be, so that if the container for the time being at the measuring station is of the same height as that for which the apparatus has just been adjusted, the microswitch 29 and the contact member 101 will come to rest at the same height, and since the contact point of the contact member 101 projects into the path of the contact point of the microswitch 29 the switch will be operated.

The microswitch 31 is attached to the feeler member 14 and there is arranged on the shaft 74 a contact arm 108 carrying a contact member 109 arranged to co-operate with the microswitch 31. The contact point of the contact member 109 and the contact point of the microswitch 31 are at the same radial distance from the centre of the shaft 74, and the contact point of the contact member projects into the path of the contact point of the microswitch. The contact arm 108 is freely mounted on the shaft 74 and is connected by means of a link 111 to a bracket 112 extending from one of the side guides 113 of the adjustable portion of the apparatus. The point of connection between the pivoted link and the contact arm is at a radial distance from the centre of the shaft 74 equal to one half the radial distance of the contact point from the centre of the shaft 14. By this means, when the feeler 14 is operated by a container of the same width as that for which the adjustable portion of the apparatus has just been adjusted, the contact point of the contact member 109 is caused to move to the same position as that to which the microswitch has been moved by the container and in so doing operates the microswitch 31. It will thus be seen that, when a container of the same dimensions as the last previous one moves into the measuring station, the equalizer switches 29 and 31 are operated with the result that the solenoids 24 and 26 remain effective and become energised on completion of the measuring operation despite the fact that the safety switch 28 is in operation.

I claim:

1. Packaging apparatus of the kind described, comprising adjustable mechanism for accommodating articles of different dimensions, a device for controlling the movement of the adjustable mechanism, said device including a movable controlling member arranged upon movement to a predetermined position to cause adjusting movement of the adjustable mechanism to a predetermined position for accommodating a given size of article, a movable feeler member connected to said controlling member and arranged to engage each article in turn as it is fed to a measuring station and to be moved thereby by an amount determined by the size of the article, such movement causing said controlling member to move to a position appropriate to the size of the article for the time being in engagement with said feeler member, thereby causing the controlling device to bring about adjustment of the adjustable

mechanism appropriate to that article, a first stop member arranged to move into the path of the articles as the leading article approaches the measuring station so as temporarily to arrest forward movement of the remaining articles, and a second stop member arranged to move into the path followed by the leading article as it reaches the measuring station, said stop members being arranged to operate in timed relationship with the operation of said controlling member so as to control the movement of the articles into and out of the measuring station.

2. Packaging apparatus of the kind described, comprising adjustable mechanism for accommodating articles of different dimensions, a device for controlling the movement of the adjustable mechanism, said device including a movable controlling member arranged upon movement to a predetermined position to cause adjusting movement of the adjustable mechanism to a predetermined position for accommodating a given size of article, a pivoted feeler member connected to said controlling member and arranged to extend transversely of the path followed by the articles so as to be moved outwardly by each article in turn as it is fed to a measuring station by an amount determined by the size of the article, such movement causing said controlling member to move to a position appropriate to the size of the article for the time being in engagement with said feeler member, thereby causing said controlling device to bring about adjustment of the adjustable mechanism appropriate to that article, a first stop member arranged to move into the path of the articles as the leading article approaches the measuring station so as temporarily to arrest forward movement of the remaining articles, and a second stop member arranged to move into the path followed by the leading article as it reaches the measuring station, said stop members being arranged to operate in timed relationship with the operation of said controlling member so as to control the movement of the articles into and out of the measuring station.

3. Apparatus according to claim 1, wherein said stop members are solenoid-operated, and wherein the adjustable mechanism comprises a safety switch arranged to be operated by any article passing through the adjustable mechanism to render said controlling member ineffective, said switch being connected in the circuit of the solenoids and arranged upon operation to cause said stop members to move into stop position.

4. Apparatus according to claim 2, wherein said stop members are solenoid-operated, and wherein the adjustable mechanism comprises a safety switch arranged to be operated by any article passing through the adjustable mechanism to render said controlling member ineffective, said switch being connected in the circuit of the solenoids and arranged upon operation to cause said stop members to move into stop position.

5. Packaging apparatus of the kind described, comprising adjustable mechanism for accommodating articles of different dimensions, a device for controlling the movement of the adjustable mechanism, said device including a movable controlling member arranged upon movement to a predetermined position to cause adjusting movement of the adjustable mechanism to a predetermined position for accommodating a given size of article, a movable feeler member con-

nnected to said controlling member and arranged to engage each article in turn as it is fed to a measuring station and to be moved thereby by an amount determined by the size of the article, such movement causing said controlling member to move to a position appropriate to the size of the article for the time being in engagement with said feeler member thereby causing said controlling device to bring about adjustment of the adjustable mechanism appropriate to that article, a first stop member arranged to move into the path of the articles as the leading article approaches the measuring station, a second stop member arranged to move into the path followed by the leading article as it reaches the measuring station, said stop members being solenoid-operated and arranged to operate in timed relationship with the operation of said controlling member so as to control the movement of the articles into and out of the measuring station, a safety switch in the adjustable mechanism arranged to be operated by any article passing through the adjustable mechanism to render said controlling member ineffective, said switch being connected in the circuit of the solenoid and arranged upon operation to cause said stop members to move into stop position, and an equalizer switch in association with said feeler member and arranged to co-operate with the adjustable mechanism in such a manner that when an article of the same size as the preceding one moves into the measuring station the equalizer switch is operated and closes the circuit that has been opened by the safety switch thereby energizing the solenoids of said stop members so as to allow that container to pass into the adjustable mechanism.

6. Packaging apparatus of the kind described, comprising adjustable mechanism for accommodating articles of different dimensions, a device for controlling the movement of the adjustable mechanism, said device including a movable controlling member arranged upon movement to a predetermined position to cause adjusting movement of the adjustable mechanism to a predetermined position for accommodating a given size of article, a pivoted feeler member connected to said controlling member and arranged to extend transversely of the path followed by the articles so as to be moved outwardly by each article in turn as it is fed to a measuring station by an amount determined by the size of the article, such movement causing said controlling member to move to a position appropriate to the size of the article for the time being in engagement with said feeler member, thereby causing the controlling device to bring about adjustment of the adjustable mechanism appropriate to that article, a first stop member arranged to move into the path of the articles as the leading article approaches the measuring station, a second stop member arranged to move into the path followed by the leading article as it reaches the measuring station, said stop members being solenoid-operated and arranged to operate in timed relationship with the operation of said controlling member so as to control the movement of the articles into and out of the measuring station, a safety switch in the adjustable mechanism arranged to be operated by any article passing through the adjustable mechanism to render said controlling member ineffective, said switch being connected in the circuit of the solenoids and arranged upon operation to cause said stop members to move into stop position, and an equalizer

switch in association with said feeler member and arranged to co-operate with the adjustable mechanism in such a manner that when an article of the same size as the preceding one moves into the measuring station the equalizer switch is operated and closes the circuit that has been opened by the safety switch thereby energizing the solenoids of said stop members so as to allow that article to pass into the adjustable mechanism.

7. Packaging apparatus of the kind described, comprising adjustable mechanism for accommodating articles of different height and width, a device for controlling the movement of the adjustable mechanism, said device including a pair of movable controlling members for controlling the movement of the adjustable mechanism as regards width and height, respectively, of the articles, said controlling members being arranged upon movement to a predetermined position to cause adjusting movement of the adjustable mechanism to predetermined positions for accommodating a given size of article, and a pair of movable feeler members connected one to each controlling member and arranged to engage the top and one side, respectively, of each article in turn as it is fed to a measuring station and to be moved thereby by an amount determined by the size of the article, such movement causing said controlling members to move to positions appropriate to the size of the article for the time being in engagement with said feeler members thereby causing the controlling device to bring about adjustment of the adjustable mechanism appropriate to that article.

8. Packaging apparatus of the kind described, comprising adjustable mechanism for accommodating articles of different height and width, a device for controlling the movement of the adjustable mechanism, said device including a pair of movable controlling members for controlling the movement of the adjustable mechanism as regards height and width, respectively, said controlling members being arranged upon movement to predetermined positions to cause adjusting movement of the adjustable mechanism to predetermined positions for accommodating a given size of article, a pair of pivoted feeler members connected one to each of said controlling members and arranged to engage the top and one side, respectively, of each article in turn as it is fed to a measuring station and to be moved thereby by an amount determined by the size of the article, such movement causing said controlling members to move to positions appropriate to the size of the article for the time being in engagement with said feeler members thereby causing the controlling device to bring about adjustment of the adjustable mechanism appropriate to that article. a first stop member arranged to move into the path of the articles as the leading article approaches the measuring station so as temporarily to arrest forward movement of the remaining articles, a second stop member arranged to move into the path followed by the leading article as it reaches the measuring station, said stop members being solenoid-operated and arranged to operate in timed relationship with the operation of said controlling members so as to control the movement of the articles into and out of the measuring station, and a safety switch arranged in the adjustable mechanism to be operated by each article passing through the adjustable mechanism to render the controlling members ineffective, said switch being connected in the cir-

cuit of the solenoids and arranged upon operation to cause said stop members to move into stop position.

9. Packaging apparatus of the kind described, comprising adjustable mechanism for accommodating articles of different dimensions, a device for controlling the movement of the adjustable mechanism, said device including a pair of movable controlling members for controlling the movement of the adjustable mechanism as regards width and height, respectively, of the articles, said controlling members being arranged upon movement to predetermined positions to cause adjusting movement of the adjustable mechanism to predetermined positions for accomodating a given size of article, a pair of movable feeler members connected one to each controlling member and arranged to engage the top and one side, respectively, of each article in turn as it is fed to a measuring station and to be moved thereby by an amount determined by the size of the article, such movement causing said controlling members to move to positions appropriate to the size of the article for the time being in engagement with said feeler members thereby causing the controlling device to bring about adjustment of the adjustable mechanism appropriate to that article, a first stop member arranged to move into the path of the articles as the leading article approaches the measuring station so as temporarily to arrest forward movement of the remaining articles, a second stop member arranged to move into the path followed by the leading article as it reaches the measuring station, said stop members being solenoid-operated and arranged to operate in timed relationship with the operation of said controlling members so as to control the movement of the articles into and out of the measuring station, a safety switch arranged in the adjustable mechanism to be operated by any article passing through the adjustable mechanism to render said controlling members ineffective, said switch being connected in the circuit of said solenoids and arranged upon operation to cause said stop members to move into stop position, and a pair of equalizer switches in association one with each of said feeler members, said equalizer switches being arranged to co-operate with the adjustable mechanism in such a manner that when an article of the same size as the preceding one moves into the measuring station said equalizer switches are operated and close the circuit that has been opened by said safety switch thereby energizing the solenoids of said stop members so as to allow that article to pass into the adjustable mechanism.

10. Packaging apparatus of the kind described, comprising adjustable mechanism for accommodating articles of different height and width, a device for controlling the movement of the adjustable mechanism, said device including a pair of movable controlling members for controlling the movement of the adjustable mechanism as regards height and width, respectively, of the articles, said controlling members being arranged upon movement to predetermined positions to cause adjusting movement of the adjustable mechanism to predetermined positions for accomodating a given size of article, a pair of pivoted feeler members connected one to each controlling member and arranged to engage the top and one side, respectively, of each article in turn as it is fed to a measuring station and to be moved thereby by an amount determined by the size of the article, such movement causing said

controlling members to move to positions appropriate to the size of the article for the time being in engagement with said feeler members, thereby causing the controlling device to bring about adjustment of the adjustable mechanism appropriate to that article, a first stop member arranged to move into the path of the articles as the leading article approaches the measuring station so as temporarily to arrest forward movement of the remaining articles, a second stop member arranged to move into the path followed by the leading article as it reaches the measuring station, said stop members being solenoid-operated and arranged to operate in timed relationship with the operation of said controlling members so as to control the movement of the articles into and out of the measuring station, a safety switch arranged in the adjustable mechanism to be operated by any article passing through the adjustable mechanism to render said controlling members ineffective, said switch being connected in the circuit of said solenoids and arranged upon operation to cause said stop members to move into stop position, and a pair of equalizer switches in association one with each of said feeler members, said equalizer switches being arranged to co-operate with the adjustable mechanism in such a manner that when an article of the same size as the preceding one moves into the measuring station said equalizer switches are operated and close the circuit that has been opened by said safety switch thereby energizing the solenoids of said stop members so as to allow that article to pass into the adjustable mechanism.

11. Packaging apparatus of the kind described, comprising adjustable mechanism for accommodating articles of different height and width, a device for controlling the movement of the adjustable mechanism, said device including a pair of movable controlling members for controlling the movement of the adjustable mechanism as regards width and height, respectively, of the articles, said controlling members being arranged upon movement to predetermined positions to cause adjusting movement of the adjustable mechanism to predetermined positions for accomodating a given size of article, a pair of movable feeler members connected one to each controlling member and arranged to engage the top and one side, respectively, of each article in turn as it is fed to a measuring station and to be moved thereby by an amount determined by the size of the article, such movement causing said controlling members to move to positions appropriate to the size of the article for the time being in engagement with said feeler members thereby causing the controlling device to bring about adjustment of the adjustable mechanism appropriate to that article, a first stop member arranged to move into the path of the articles as the leading article approaches the measuring station so as temporarily to arrest forward movement of the remaining articles, a second stop member arranged to move into the path followed by the leading article as it reaches the measuring station, said stop members being arranged to operate in timed relationship with the operation of said controlling members so as to control the movement of the articles into and out of the measuring station, a safety switch arranged in the adjustable mechanism to be operated by each article passing through the adjustable mechanism to render the controlling members ineffective, and a pair of equalizer switches in association one with each of said feeler members, said

equalizer switches being arranged to co-operate with the adjustable mechanism in such a manner that when an article of the same size as the preceding one moves into the measuring station said equalizer switches are operated to render the safety switch inoperative thereby allowing that article to pass into the adjustable mechanism.

12. Packaging apparatus of the kind described, comprising adjustable mechanism for accommodating articles of different height and width, a device for controlling the movement of the adjustable mechanism, said device including a pair of movable controlling members for controlling the movement of the adjustable mechanism as regards height and width, respectively, said controlling members being arranged upon movement to predetermined positions to cause adjusting movement of the adjustable mechanism to predetermined positions for accommodating a given size of article, a pair of movable feeler members connected one to each of said controlling members and arranged to engage the top and one side, respectively, of each article in turn as it is fed to a measuring station and to be moved thereby by an amount determined by the size of the article, such movement causing said controlling members to move to positions appropriate to the size of the article for the time being in engagement with said feeler members thereby causing the controlling device to bring about adjustment of the adjustable mechanism appropriate to that article, a safety switch arranged in the adjustable mechanism to be operated by each article passing through the adjustable mechanism to render the controlling members ineffective, and a pair of equalizer switches in association one with each of said feeler members, said equalizer switches being arranged to co-operate with the adjustable mechanism in such a manner that when an article of the same size as the preceding one moves into the measuring station said equalizer switches are operated to render the safety switch inoperative thereby allowing that article to pass into the adjustable mechanism.

13. Packaging apparatus of the kind described, comprising adjustable mechanism for accommodating articles of different height and width, a device for controlling the movement of the adjustable mechanism, said device including a pair of movable controlling members for controlling the movement of the adjustable mechanism as regards height and width, respectively, said controlling members being arranged upon movement to predetermined positions to cause adjusting movement of the adjustable mechanism to predetermined positions for accommodating a given size of article, and a pair of pivoted feeler members connected one to each of said controlling members and arranged to engage the top and one side, respectively, of each article in turn as it is fed to a measuring station and to be moved thereby by an amount determined by the size of the article, such movement causing said controlling members to move to positions appropriate to the size of the article for the time being in engagement with said feeler members thereby causing the controlling device to bring about adjustment of the adjustable mechanism appropriate to that article.

14. Packaging apparatus of the kind described, comprising adjustable mechanism for accommodating articles of different height and width, a device for controlling the movement of the ad-

justable mechanism, said device including a pair of movable controlling members for controlling the movement of the adjustable mechanism as regards height and width, respectively, said controlling members being arranged upon movement to predetermined positions to cause adjusting movement of the adjustable mechanism to predetermined positions for accommodating a given size of article, a pair of pivoted feeler members connected one to each of said controlling members and arranged to engage the top and one side, respectively, of each article in turn as it is fed to a measuring station and to be moved thereby by an amount determined by the size of the article, such movement causing said controlling members to move to positions appropriate to the size of the article for the time being in engagement with said feeler members thereby causing the controlling device to bring about adjustment of the adjustable mechanism appropriate to that article, a first stop member arranged to move into the path of the articles as the leading article approaches the measuring station so as temporarily to arrest forward movement of the remaining articles, and a second stop member arranged to move into the path followed by the leading article as it reaches the measuring station, said stop members being arranged to operate in timed relationship with the operation of said controlling members so as to control the movement of the articles into and out of the measuring station.

15. Packaging apparatus of the kind described, comprising adjustable mechanism for accommodating articles of different height and width, a device for controlling the movement of the adjustable mechanism, said device including a pair of movable controlling members for controlling the movement of the adjustable mechanism as regards height and width, respectively, said controlling members being arranged upon movement to predetermined positions to cause adjusting movement of the adjustable mechanism to predetermined positions for accommodating a given size of article, a pair of pivoted feeler members connected one to each of said controlling members and arranged to engage the top and one side, respectively, of each article in turn as it is fed to a measuring station and to be moved thereby by an amount determined by the size of the article, such movement causing said controlling members to move to positions appropriate to the size of the article for the time being in engagement with said feeler members thereby causing the controlling device to bring about adjustment of the adjustable mechanism appropriate to that article, a first stop member arranged to move into the path of the articles as the leading article approaches the measuring station so as temporarily to arrest forward movement of the remaining articles, a second stop member arranged to move into the path followed by the leading article as it reaches the measuring station, said stop members being solenoid-operated and arranged to operate in timed relationship with the operation of said controlling members so as to control the movement of the articles into and out of the measuring station, a safety switch in the adjustable mechanism arranged to be operated by any article passing through the adjustable mechanism to render said controlling members ineffective, said switch being connected in the circuit of the solenoids and arranged upon operation to cause said stop members to move into stop position, and an equalizer switch in as-

sociation with said feeler members and arranged to co-operate with the adjustable mechanism in such a manner that when an article of the same size as the preceding one moves into the measuring station the equalizer switch is operated and closes the circuit that has been opened by the safety switch thereby energising the solenoids of said stop members so as to allow that article to pass into the adjustable mechanism.
